UNITED STATES PATENT OFFICE.

GEORGE C. MURRAY, OF CHICAGO, ILLINOIS.

CAR-ROOF CONSTRUCTION.

1,319,237.

Specification of Letters Patent.

Patented Oct. 21, 1919.

Application filed January 2, 1915. Serial No. 144.

To all whom it may concern:

Be it known that I, GEORGE C. MURRAY, a citizen of the United States, residing at Chicago, in the county of Cook and State 5 of Illinois, have invented certain new and useful Improvements in Car-Roof Construction, of which the following is a specification.

This invention relates to improvements in 10 car roof construction, and has for its object to provide a new and improved car roof, simple in construction, and water-tight, whereby leakage of water or the like, into the car is prevented.

15 My construction is designed and intended to prevent leakage of water, or the like, through the roof, even under severe hose tests which precede the use of cars in many instances where damageable goods are to be 20 shipped therein.

It is the principal object of my invention to provide a car roof of simple construction comprising roof sheets supported by and attached to carlines, which in turn are supported by and attached to the side plates. I construct these carlines of channel beams 25 with the channels facing upwardly, and preferably arch the same so that the tendency of any water or fluid, or even dust or 30 cinders, which may possibly enter these channels will be to drain outwardly toward the sides of the car. The roof sheets are attached thereto, and the carlines are protected as well as the edges of the roof sheets, 35 so that the entrance of water, or the like, into the car is impossible, and it is practically impossible for the same to enter the channels of the carlines. However, as stated above, in the event that any fluid or solid 40 matter does enter the carlines, the latter are arranged to provide drainage of the same outwardly from the car.

Another object of my invention is to provide, in combination with the roof structure, 45 means for supporting and attaching the running board.

These and other objects will be more fully set forth and described in the following specification, and shown in the accompanying 50 drawings, in which—

Figure 1 is a plan view of a car a por-

tion of the roof being broken away, showing my invention applied thereto.

Fig. 2 is an end elevation of the same.

Fig. 3 is a side elevation of a portion of 55 the car roof.

Fig. 4 is a perspective view of the roof structure, showing the roof sheets removed.

Fig. 5 is a detail section, taken along the 60 line 5—5 of Fig. 1.

Fig. 6 is a detail section, taken along the line 6—6 of Fig. 1.

Fig. 7 is a section, taken along the line 7—7 of Fig. 6.

Fig. 8 is a perspective view of one of the 65 engageable blocks.

Fig. 9 is a perspective view of the end of one of the cover strips.

Fig. 10 is a detail of a corner of one of 70 the roof strips.

Fig. 11 is a detail of one of the cap members; and

Fig. 12 is a section taken along the line 12—12 of Fig. 2.

Like numerals refer to like elements 75 throughout the drawings. 10 designates generally a car having the side walls 10^a. Carried at the upper portion of the side walls are the side plates 11, as shown in Figs. 4 and 6, for example. 80 Extending across between these side plates 11 are the carlines 12, each comprising a channel member having the upwardly extending side flanges 12^a, the trough or channel 12^b being arranged to face upwardly, as shown in the drawings. Angles 13 are attached to the side plates 11 and side flanges 12^a of the carlines 12, by means of rivets, or the like. Located between the side plates are the purlins 14, comprising angle 85 bars in the construction shown. The carlines are secured to these purlins by suitable angles 14^a at one side of the carlines, as shown for example in Figs. 1 and 4. Braces 15, also constructed of angle bars, extend 90 across between the purlins and the other side of the carlines, and are attached thereto at their extremities by rivets, or the like, and are also attached at their extremities to the purlins, as clearly shown in Fig. 4. Intermediate the extremities of the braces 15 are 95 provided plates or strips 16 extending be-

tween the carlines 12 and the braces 15, and attached to both said members by rivets, or the like. These braces are bent around the strip 16 sufficiently to permit their application, as shown in Fig. 4.

5 Mounted at suitable intervals in the channels 12^b of the carlines 12 are the engageable or block members 17,—see Fig. 8, for example. These block members have 10 the side flanges 17^a extending downwardly below the bottom 17^b of the blocks, as shown in Fig. 5, for example. This construction provides a drainage space 18 between the blocks and the bottom of the channels 12^b, 15 as is clearly shown in Fig. 6. These flanges 17^a are spaced from the sides 17^c of the block proper, and extend in opposite directions, and are enlarged adjacent their extremities and provided with apertures 17^e. 20 These flanges and blocks are constructed so that the former will contact with the side flanges 12^a of the carlines 12, and are secured thereto by means of rivets, or other suitable fastening means, passing through 25 the apertures 17^e. The construction of the flanges 17^a to extend in opposite directions provides a strong and simple fastening means, and at the same time renders the block members 17 reversible. Provided in the 30 blocks, and extending inwardly thereinto from one face thereof, are the recesses 17^d, with each of which communicates a slot 17^f in the top of the blocks, providing, in effect, a T-shaped open-ended slot, for a purpose to be hereinafter described. Roof 35 sheets 19 of sheet metal, or the like, are provided, these roof sheets being supported upon the purlins and having their sides bent upwardly and downwardly, as indicated by numeral 19^a, see Fig. 10. These bent portions 19^a project over the side flanges 12^a and downwardly into the channels 12^b. These roof sheets are further 40 slightly offset at 19^b to fit over the horizontal flanges of the braces 15 and angles 14^a, as is shown in Fig. 5, for example.

Fitting over the bent portions 19^a of the roof sheets 19, and completely covering the channeled carlines 12, are what I term the 45 cover strips 20 having the downwardly inclined side portions 20^a resting on and closely contacting with the corresponding roof sheets 19,—see Fig. 5, for example. To maintain these cover strips 20 firmly 50 fixed in position, I provide the bolting members 21, having their heads 21^a arranged to fit in the T-shaped slots 17^d of the blocks 17. These bolts 21 extend upwardly through suitable holes or apertures in the 55 cover strips 20, and washers 22 are fitted thereon around said bolts, the washers and cover strips being closely pressed and held against the block 17 by means of the nuts 23 screwed on the bolts 21. It will be ap-

parent that by this construction the channels, as well as the sides of the roof sheets, are thoroughly covered and protected and streams of water, such as from a hose or the like, directed on or over the roof are prevented from flowing into the car, and even if any moisture should be driven upwardly between the sides 20^a of the cover strips 20 and the roof sheets 19, such water will only penetrate into the channels 12^b and will be permitted to flow outwardly 75 therefrom, there being no apertures in or adjacent the bottom of these channels. Furthermore, the arched form of the carlines 12 is such as to cause the flow of fluid outwardly toward the sides of the car. At 80 the ends of the carlines 12 the roof sheets 19 are cut away, as indicated by the numeral 19^c. The roof sheets further have their outer side portions 19^e bent downwardly and attached by nails, or the like, 85 to the side of the car, as shown in Fig. 3, for example. The cover strips 20 have their ends 20^b bent down, as shown in Fig. 9, and the extremities 20^e of the side portions 20^a are bent around, as is shown in 90 Fig. 9. The downwardly bent portion 20^b terminates above the floor of channel 12^b, as shown in Fig. 6, so that flow of water, or the like, from the carlines 12 is not effected or prevented.

95 Fitting over the ends of the carlines, cover strips, and roof sheets are the caps 25,—see Figs. 6 and 11, for example, the caps being provided with the top portion 25^a secured in place by means of one of the 100 bolts 21, as is shown in Fig. 6. These caps are further provided with the downwardly projecting portions 25^b, a portion of which is outwardly bent to provide a drainage space 25^c therebetween and the side of the 105 car. A bolt 26 extends through the portion 25^b of caps 25 and the side plates 11, as shown in Fig. 6.

Mounted upon the cover strips 20, intermediate their extremities and adjacent the 110 central portion of the car, are the brackets 27 having the bases 27^a, which are attached by the adjacent bolts 21 to the respective block members 17. These brackets are further provided with the top flanges 27^b, upon 115 which are supported, and to which are secured, the usual running boards 28.

It will be apparent that I have provided a simple car roof, water-tight, and I have further provided an improved structure 120 which is easy to assemble, and which reduces the weight of ordinary car roofs to a minimum.

125 It will also be apparent that my invention is susceptible of modifications and improvements, and I do not wish to be restricted to the form shown and described beyond the scope of the appended claims.

What I claim is:

1. A car roof structure comprising side plates, channeled carlines extending therebetween and having their channels facing upwardly, purlins, and braces extending between a pair of said purlins and attached thereto and to said carlines.
2. A car roof structure comprising side plates, channeled carlines extending therebetween and having their channels facing upwardly, purlins, braces extending between a pair of said purlins and attached thereto and to said carlines, and angles attached to said purlins and to said carlines.
3. A car roof structure comprising side plates, channeled carlines extending therebetween and having their sides and channels directed upwardly, the lower walls of said carlines being imperforate, roof sheets having portions bent upwardly and over the sides of said carlines and downwardly within the channels of said carlines, cover strips mounted over said carlines and having their lateral edges bent downwardly over the bent portions of said roof sheets along the outer sides of said carlines, block members mounted within said carlines and having parts thereof spaced upwardly from the lower walls of said carlines to permit moisture to pass therethrough, and means for detachably securing said cover strips and roof sheets to said carlines.
4. A car roof structure comprising side plates, purlins located inwardly of said side plates, channeled carlines extending between said side plates and resting on said side plates and said purlins, said carlines having their channels and side flanges directed upwardly, flanged members attached to the sides of said carlines and connected to said side plates and said purlins, roof sheets supported on said side plates and said purlins and having portions thereof bent up and over the side flanges of said carlines, cover strips mounted over said carlines and having side flanges extending downwardly and in contact with the upwardly bent portions of said roof sheets, block members attached to the side flanges of said carlines above the lower walls thereof and spaced from said lower walls, and means for securing said cover strips to said block members.
5. A car roof structure comprising side plates, channeled carlines extending therebetween and having their sides and channels facing upwardly, roof sheets having portions bent up and over the sides of said carlines, cover strips mounted over the bent portions of said roof sheets and over said carlines, means to attach said cover strips and roof sheets to the carlines, said means comprising block members mounted in the channels of said carlines, said block members being arranged with a space therebetween and the bottom of said channels and being further attached to the sides of said carlines, and means to attach said cover strips to said block members.
6. A car roof structure comprising side plates, channeled carlines extending therebetween and having their sides and channels facing upwardly, roof sheets having portions bent up and over the sides of said carlines, cover strips mounted over the bent portions of said roof sheets and over said carlines, means to attach said cover strips and roof sheets to the carlines, said means comprising block members mounted in the channels of said carlines, said block members being provided with T-shaped slots, said last-named means comprising bolting members having portions mounted in said slots.
7. A car roof structure comprising side plates, purlins located inwardly of said side plates, channeled carlines extending between said side plates and resting on said side plates and said purlins, said carlines having their channels and side flanges directed upwardly, flanged members attached to the sides of said carlines and connected to said side plates and said purlins, roof sheets supported on said side plates and said purlins and having portions thereof bent up and over the side flanges of said carlines, cover strips mounted over said carlines and having side flanges extending downwardly and in contact with the upwardly bent portions of said roof sheets, block members attached to the side flanges of said carlines above the lower walls thereof and spaced from said lower walls, means for securing said cover strips to said block members, and cap members secured to said block members adjacent the ends of said carlines and extending downwardly over the ends of the channels.
8. A car roof structure comprising channeled carlines, engageable members mounted therein and secured to the side walls thereof, brackets mounted on said carlines and attached to said engageable members, and a running board supported upon said brackets.
9. A car roof structure comprising side plates, purlins located inwardly of said side plates, channeled carlines extending between said side plates and resting on said side plates and said purlins, said carlines having their channels and side flanges directed upwardly, flanged members attached to the sides of said carlines and connected to said side plates and said purlins, roof sheets supported on said side plates and said purlins and having portions thereof bent up and over the side flanges of said carlines, cover

strips mounted over said carlines and having side flanges extending downwardly and in contact with the upwardly bent portions of said roof sheets, block members attached to the side flanges of said carlines above the lower walls thereof and spaced from said lower walls, means for securing said cover strips to said block members, brackets attached to said block members adjacent the center of the car, and a running board supported upon said brackets.

10. A car roof structure comprising side plates, purlins spaced inwardly from said side plates, channeled carlines supported on said side plates and purlins and secured thereto, said carlines having their channels directed upwardly, angle members secured

to said carlines and connected to said side plates and purlins, roof sheets supported on said side plates and carlines and having portions thereof bent upwardly and over the sides of said carlines, cover strips extending over said carlines and having side flanges directed downwardly in contact with the upwardly bent portions of said roof sheets, and means for securing said roof sheets to said carlines. 20 25

In testimony whereof, I have subscribed my name.

GEORGE C. MURRAY.
